(57) **CLAIM**

The ornamental design for a base panel connector, as shown and described.

DESCRIPTION

FIG. 1 is a top, rear and right side perspective view of a base panel connector, showing the new design;

FIG. 2 is a top, front and left side perspective view thereof;

FIG. 3 is a top, front and right side perspective view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front elevation view thereof;

FIG. 9 is a rear elevation view thereof; and,

FIG. 10 is a bottom, front and left side perspective view thereof.

The dashed lines in Figures represent environment for illustrative purposes and do not constitute part of the claimed design.
